Patented Mar. 8, 1960

187,396

DECANTER

Ernest L. Du Pree, New York, N.Y., assignor to Schenley Industries, Inc., New York, N.Y., a corporation of Delaware

Application July 17, 1959, Serial No. 56,817

Term of patent 14 years

(Cl. D58—6)

Figure 1 is a side elevational view of a decanter embodying my new design, the other three sides thereof being substantially the same;

I claim:

The ornamental design for a decanter, as shown and described.
